HAIR WAVING APPARATUS

Filed April 30, 1930

INVENTOR:
August H. Opperman,
BY
E. T. Silvius,
ATTORNEY.

UNITED STATES PATENT OFFICE

AUGUST H. OPPERMANN, OF INDIANAPOLIS, INDIANA

HAIR-WAVING APPARATUS

Application filed April 30, 1930. Serial No. 448,686.

This invention relates to an improved hair-waving apparatus adapted to be used in the operations of curling or waving hair by the application of heat, the general character of 5 hair-waving apparatus adapted for facilitating rapid operations being disclosed in Letters Patent granted to me February 18, 1930, No. 1,747,787; the present invention having reference more particularly to means 10 for adjustably supporting and controlling electric heaters whereby the operations of waving human hair are performed.

An object of the invention is to provide an improved stand of electric heaters and controlling apparatus for hair-waving operations, which shall be of simple and efficient construction and not be costly to manufacture.

Another object is to provide improved 20 means for adjustably supporting electric heaters necessary in the operations of hair-waving and hair curling to advantage, without depending upon circuit wires for supporting the heaters, which apparatus shall 25 be so constructed as to permit rapid assembly of parts and also replacement of parts that might become necessary as a consequence of accident, long use and wear of operating parts.

30 A further object is to provide new and simple means whereby to cause frictional resistance on controlling cords that may be used to adjustably support the electric heaters, without entailing the use of counterweights 35 for the heaters and necessary means for guiding the counterweights, an aim of the present invention being to provide noiseless cord-controlling means in a dome of small bottom area that shall offer the least obstruction to convenient manipulation of the heaters.

40 A still further object is to provide an improved unit of adjusting devices which shall be of such construction as to be adapted to noiselessly operate in an improved manner, 45 and which shall not be costly to manufacture and shall be adapted to be durable and economical in use.

With the above-mentioned and other objects in view, the invention consists in a novel 50 unitary controlling apparatus and an im-

proved supporting and enclosing dome therefor, the invention consisting also further in the novel parts and combinations and arrangements of parts as hereinafter particularly described and further defined in the 55 claims appended hereto.

Referring to the accompanying drawings—Figure 1 is an elevation of the apparatus as preferably constructed, a portion of the dome being in vertical section to clearly show 60 improved structural features; Fig. 2 is a perspective view of one of the frictional control devices of the invention on an enlarged scale; Fig. 3 is an enlarged view of one of the cords whereby the heaters are supported, the cord 65 being loosely arranged in connection with its guides, the manner of reaving the cord to afford friction resistance being clearly illustrated; Fig. 4 is a top plan of the main part of the dome, minus the cover part of the 70 dome, the arrangement of the controlling devices or cord tensioners being shown in horizontal section; Fig. 5 is an elevation of a novel holder or controlling device base and a number of the devices arranged therein. 75

Similar reference characters in the different figures of the drawings indicate corresponding elements or features of construction herein referred to in detail.

As preferably constructed the new hair-waving apparatus comprises a portable base 1 and a standard comprising a main part 2 secured thereto and having a curved arm 3 that reaches laterally a suitable distance to conveniently support the dome of the apparatus. 80 The dome is composed of spun or die-pressed sheet metal preferably composed of two principal parts to constitute a hollow housing, there being a main or lower part that is substantially urn-shaped, and a semi-globular cover or top part. The main part has a small circular bottom 4 and ornamentally flared side wall 5 of which a portion is only slightly inclined to constitute a bench portion 6, the remaining upper portion of the 85 wall being further flared and having a joint seat 7 at its top that is provided with a number of small bolt holes 8. The cover part 9 is provided with a flange on its edge that is supported upon the seat 7, the middle portion of 90 95 100

the cover having a depressed portion 10 as preferably constructed, and the upper and lower parts of the housing are detachably secured together by means of a suitable bolt or screws 11.

- 5 A hollow or cup-shape holder is provided which has a bottom 12 and cylindrical side wall 13 having a flared upper portion 14, the cup being centrally arranged upon the housing bottom 4. A suitable number of elastic controlling devices or tensioners are provided, one for each electric heater required, two of the tensioners being shown as sufficient to an understanding of the invention 10 and comprising base portions 15 and 15' and main operative portions 16 and 16' respectively, the base portions being arranged in the cup against the wall 13 thereof and fixedly secured therein by means of a cup-shaped 15 core 17 forced into place and preferably having a bottom 18 supported on the bottom 12. A center rod 19 is provided which is inserted through the depressed portion 10 of the cover portion of the bolt being screw-threaded and 20 having a nut 20 thereon that engages the bottom 18 and also a nut 21 engaging the under side of the bottom 4. The upper portion of the rod also is screw-threaded and extends through the depressed portion 10 of the cover 25 part and is screwed into and through the terminal portion of the standard portion 3. A nut 22 is arranged beneath the depressed portion 10 and a nut 23 is arranged on the rod upon the bottom of the depressed portion 30 35 to secure the principal parts of the housing together in a firm manner, and the rod preferably is provided with a lock nut 24 engaging the upper face of the standard arm. The housing is preferably secured against rotation under the arm by means of a bolt 25 inserted through the cover 9 and screwed 40 through the arm portion 3 and provided on its end with a lock nut 26.

The bench portion 6 of the housing has a 45 suitable number of apertures 27, and 27' to accommodate the required number of electric receptacles 28, 28', the receptacles being conventionally connected with circuit wires 29 adapted to have plugs 30, 30' detachably 50 connected thereto and to which electric cables 31, 31' are connected to conduct electric energy to suitable curler heaters, each heater preferably being of the clamping type comprising arms 32 and 33 pivotally connected 55 together and having curved heater plates 34 and 35 thereon respectively that are adapted to be applied to hair coils in a customary manner.

60 A supporting cord 36 is provided for each electric heater and is suitably attached thereto, one end of the cord being connected to the lever 32, the cords extending through suitable guide holes 37, 37' and into the housing, each hole having a guide bushing 38 therein 65 through which the cord loosely extends to an

elastic tensioner. Each cord has a stop collar 39 thereon that is counterbored in its outer portion to receive a knot 40 with which the cord is provided to prevent the cord from slipping through the collar when the latter is stopped against the bushing. The inner side of the housing wall is provided with a guide eye having a shank 41 which is conveniently fastened to the wall by a bushing suitably upset to constitute a hollow rivet. 70 Preferably the shank has two guide eyes 42 and 43 integral therewith that are arranged slightly higher than the inner end of the bushing. Each tensioning controller is provided on its outer side with guide eyes 44 and 45 integral with a shank 46 set into a perforation 47 in the controller adjacent to its upper end and secured in place by bending the shank over the top of the plate. The cord may be passed through the eye 44 and back to the eye 42 and secured thereto as indicated in Fig. 1 when the eye 44 affords sufficient frictional resistance to support the type of heater that may be supplied. Preferably the cord is passed from the guide bushing 38 75 to and through the eye 45, thence to and through the eye 43, thence the eye 44 and thence to the eye 42 and having a knot 48 or other means securing the end of the cord to the eye. The required electric circuit for conducting current into the housing is afforded by means of a cable 49 and conveniently distributing the electric current to the various plug receptacles, as customary. 80

85 Preferably each elastic controller in practice is composed of a flat strip of tempered steel similar in character to clock spring material. Each shank or base portion 15 is straight while the operative main portion 16 is slightly curved so as to extend inwardly 90 or towards the rod 19 when primarily set in place in the holding cup and is subsequently sprung outward by the supporting cord 95 when threaded through the eyes, so that the controller is then under tension and puts the cord under tension. 100

105 In practical use strands of hair are suitably prepared for treatment, the subject to be treated being seated under the dome or housing and the heaters drawn down and clamped to the prepared hair strand to be subjected to the electric heat in a well-known process. As the heater is drawn down to convenient position for use the supporting cord is drawn out and pulls the controller 110 outward or over towards the wall of the housing, the frictional resistance caused by the guide eyes affording sufficient tension to enable the cord to support the weight of the heater in the position in which it may be placed, the controlling tensioner maintaining the cord in taut condition. As the operator lifts the heater after use all slack in the supporting cord is taken up by the elastic controller so that with the aid of the fric- 115 120 125 130

tional resistance of the cord in the eyes the heater may be supported adjustably or fully up with the stop collar 39 bearing against the bushing 38. The various adjustments of the heaters to different levels are quickly made by the operator as result of merely lifting or by pulling down the heater.

What is claimed is:

1. A hair-waving apparatus having a housing provided therein with elastic tensioners having each a guide eye, and cords secured to the housing and extending through the guide eyes respectively and out through the wall of the housing.

2. A hair-waving apparatus having a hollow housing provided therein with upstanding laterally-elastic controllers, the upper portion of each controller having a device to co-operate in control of a longitudinally adjustable supporting cord in the housing.

3. A hair-waving apparatus having a movable frictional resistance eye provided with a laterally-elastic controller, a housing supporting the controller, and a flexible supporting cord anchored to the housing and leading through the eye and the wall of the housing.

4. A hair-waving apparatus having a housing and flexible heater-supporting cords anchored therein and extending out of the housing, and elastic controllers anchored in the housing and provided with tensioning connections co-operating with the cords respectively.

5. A hair-waving apparatus having a hollow housing and a cylindrical holder fixed in the lower portion thereof, a plurality of adjustable supporting cords extending through the housing wall and anchored at their inner ends to the wall, and a plurality of laterally-elastic controllers having base portions fixedly secured in the holder, the controllers extending upwardly and having tensioning connections with the cords.

6. A hair-waving apparatus including a hollow housing having guide holes in the wall thereof and frictional resistance eyes supported on the wall above the holes, a series of flexible heater-supporting cords extending movably through the guide holes respectively, each cord being anchored to one of the eyes and leading through another one, and a series of elastic controllers anchored in the housing and provided each with a plurality of tensioning eyes co-operating with one of the series of cords.

7. A hair-waving apparatus including a hollow housing, a cup fixedly secured in the lower portion of the housing, a plurality of laterally-elastic controllers having base portions vertically secured in the cup, the upper portions of the controllers having tensioning eyes shiftably carried thereby, tensioning eyes fixedly supported in the housing by the wall

thereof, and flexible supporting cords anchored in the housing and each extending through a fixed eye and the eyes carried by one of the controllers, each cord extending through the housing wall and having a stop device on the outer portion thereof.

8. A hair-waving apparatus including a hollow housing having an urn-shaped lower part, a dome-shaped cover part on the lower part, a cup supported upon the bottom portion of the lower part, a plurality of laterally elastic tensioning plates upstanding in the cup fixedly secured thereto, each plate having cord guides on its upper portion, a center rod secured to the middle portion of the cover part and also to the bottoms of the lower part of the housing and the cup, supporting cords anchored to the housing and extending through the cord guides and out through the wall of the lower part thereof, and other guides for the cords supported on the housing wall.

9. In hair-waving apparatus, the combination with a plurality of flexible supporting cords anchored at one portion thereof, and electric heaters supported by the cords, of an upright cylindrical holder, a plurality of laterally-elastic controllers upstanding in the holder and secured thereto, and tensioning cord guides carried by the upper portions of the controllers respectively and cooperating with the cords.

10. In hair-waving apparatus, the combination of a housing part having a bottom, a cup having a bottom and a cylindrical side wall, the cup bottom being seated upon the housing bottom and the wall having a flared upper portion, a plurality of laterally-elastic controllers having flat base portions vertically arranged on the inner side of said cup wall, a hollow core engaging the inner sides of said base portions and having a bottom seated upon the cup bottom, a center rod extending through all of said bottoms, a nut on said rod bearing upon said core bottom, and a nut on said rod bearing on said housing bottom, with heater-supporting cords anchored to the housing part and tensioned on the upper portions of the controllers.

In testimony whereof, I affix my signature on the 28th day of April, 1930.

AUGUST H. OPPERMANN.
